UNITED STATES PATENT OFFICE.

JOHN DOYLE, OF HOBOKEN, NEW JERSEY, ASSIGNOR TO HIMSELF, AND C. COLES DUSENBURY, OF WHITE PLAINS, NEW YORK.

HAND-PROTECTOR.

SPECIFICATION forming part of Letters Patent No. 276,231, dated April 24, 1883.

Application filed September 4, 1882. (No model.)

To all whom it may concern:

Be it known that I, JOHN DOYLE, of Hoboken, in the county of Hudson and State of New Jersey, have invented an Improvement in Hand-Protectors, of which the following is a specification.

The object of this invention is to enable a workman to grasp any article at some distance from the hand, so that the hand may be protected from danger.

It is well known that circular saws very often injure the hands of the workmen. This improvement enables the piece of wood to be grasped and held while being passed over the saw, the hand of the workman not coming dangerously near to the saw. The same instrument is useful in handling articles that are hot—such as crucibles, castings, forgings, &c.—without the risk of the hand being burned, and the instrument may be used for any other purpose wherever available.

In the drawings, Figure 1 is a plan view of the implement with the hand applied to the same. Fig. 2 is a side view, and Fig. 3 is a section at the line *xx*.

I make use of a stock, *a*, or bar, upon which is received the shell *b*, of sheet metal or other material, having at its ends the flanges *c*, *d*, that are turned downwardly.

h h' h² h³ h⁴ are longitudinal shafts, bars, or tubes that pass through the flanges *c* and *d* of the shell *b*, and at the back end each shaft is bent downwardly as a crank, and terminates with a loop or finger-piece, *k*, of suitable shape 35 to receive the fingers or against which the finger may rest; and at the forward end the respective longitudinal shafts are bent downwardly and curved, and provided with windings or pads of leather, cotton, or other suitable material—such as metal or asbestos—to form the thumb *l* and fingers *m n o p*. The loops *k* or finger-pieces are in a position adapted to receive the fingers of the hand, and the loop *k'* the thumb, as shown in Fig. 1, and the hand is above the stock *a*, so that the instrument is grasped by the pressure of the fingers and thumb as they seize and hold the loops,

the loops and crank-arms swinging as the fingers are closed, and in so doing the bars or longitudinal shafts *h h' h² h³ h⁴* are partially turned, and the fingers and thumb of the hand-protector receive a motion analogous to that of the human hand; hence the protector can be made to grasp and hold a piece of wood or metal, (shown at *w*), or let go of the same, and the fingers of the protector being so far away from the operative's hand that it is not necessarily brought into dangerous proximity to a circular saw, or to any place where there is risk of injury from cutting tools, heat, or any other source of danger, and at the same time the protector grasps the article to be operated upon with the required firmness. This protector is a new article of manufacture.

I am aware that artificial hands have been made use of; but the fingers of such hands are not adapted to being moved by the actual fingers of the natural hand.

I do not limit myself to the materials employed, as the shafts that extend from the natural fingers to the artificial fingers may be of wood or other suitable material, and solid or hollow, and the shell may be in the form of a frame, if desired. In some instances it will not be necessary to provide more than two fingers and the thumb.

I claim as my invention—

1. The combination, with the shell *a*, having the flanges *b c*, of the shafts passing longitudinally through the flanges, the crank-shaped ends and loops to such shafts, the thumb and finger-pieces at the bent ends of such shafts, and the stock *a*, substantially as set forth.

2. The hand-protector having artificial fingers and thumb at one end of the instrument, and loops or finger-pieces near the other end of the instrument, for the fingers and thumb of the natural hand, substantially as set forth.

Signed by me this 31st day of August, A. D. 1882.

JOHN DOYLE.
